UNITED STATES PATENT OFFICE

159,124

GAME BOARD

Fred W. Whetstone, Salem, Oreg.

Application December 14, 1949, Serial No. 6,616

Term of patent 7 years

(Cl. D34—5)

To all whom it may concern:

Be it known that I, Fred W. Whetstone, a citizen of the United States of America, residing at Salem, in the county of Marion and State of Oregon, have invented a new, original, and ornamental Design for Game Boards, of which the following is a specification, reference being had to the accompanying drawing, forming part thereof.

In the drawings:

I claim:

The ornamental design for a game board, as shown.

FRED W. WHETSTONE.
